DESIGN FOR A TIMEPIECE DIAL

William M. Hansen, Niles, Mich.

Application March 14, 1947, Serial No. 137,606

Term of patent 14 years

(Cl. D42—10)

To all whom it may concern:

Be it known that I, William M. Hansen, a citizen of the United States, residing at Niles, in the county of Berrien and State of Michigan, have invented a new, original, and ornamental Design for Timepiece Dial, of which the following is a specification, reference being had to the accompanying drawing, forming part thereof, in which the figure is a front elevational view of a timepiece dial, showing my new design.

I claim:

The ornamental design for a timepiece dial, as shown.

WILLIAM M. HANSEN.
